PORTABLE SUN BATHING REFLECTOR

Gerald A. Besnah, Milwaukee, Wis., assignor to Solar Products, Incorporated, Milwaukee, Wis.

Filed May 28, 1958, Ser. No. 51,114

Term of patent 3½ years

(Cl. D83—1)

FIG. 1 is a front perspective view of a portable sun bathing reflector, showing my new design;

FIG. 2 is a rear perspective view, thereof, on a slightly reduced scale; and

FIG. 3 is a right end elevational view thereof on an enlarged scale.

I claim:

The ornamental design for a portable sun bathing reflector, as shown.
